UNITED STATES PATENT OFFICE.

DEXTER C. BAKER, OF OAKLAND, CALIFORNIA, ASSIGNOR TO BAKER-HANSEN MANUFACTURING COMPANY, OF OAKLAND, CALIFORNIA, A CORPORATION OF CALIFORNIA.

LIQUID SEAL AND SEPARATOR.

1,185,274.

Specification of Letters Patent.

Patented May 30, 1916.

Application filed November 17, 1914. Serial No. 872,563.

To all whom it may concern:

Be it known that I, DEXTER C. BAKER, a citizen of the United States, residing at Oakland, in the county of Alameda and 5 State of California, have invented new and useful Improvements in Liquid Seals and Separators, of which the following is a specification.

This invention relates to a liquid seal and 10 separating attachment for rotary pumps, compressors, and the like.

It is one of the objects of the present invention to provide a liquid circulating attachment for rotary pumps, compressors, 15 and the like which is primarily adapted to circulate sufficient liquid through the pump to form a seal between the cylinder and piston vanes.

Another object of the invention is to provide 20 means for separating the sealing liquid from the air before this is finally permitted to discharge, and to provide means for regulating the volume of liquid circulated through the pump or compressor.

25 Further objects will hereinafter appear.

The invention consists of the parts and the construction and combination of parts as hereinafter more fully described and claimed, having reference to the accompanying 30 drawings in which—

Figure 1 is a side elevation, partly in section, showing the application of the invention to a rotary type of compressor. Fig. 2 is a cross section of the separating chamber 35 on line 2—2, Fig. 1. Fig. 3 is a transverse vertical section on line 3—3, Fig. 1.

More particularly described, A indicates the cylinder, 2 the piston, 3 the vanes, 4 the intake port and 5 the exhaust or discharge 40 port of a suitable form of rotary compressor. Connected with the exhaust port by means of a nipple 6 is a casting 7 in which is formed an interior chamber 8, and formed interior of the chamber is a baffle plate 9 and a stand-pipe 10. Pipe 10 extends nearly 45 to the top of the chamber and the lower end of same is connected with nipple 6. The casting is otherwise provided with a final outlet opening 11 positioned on the opposite 50 side of baffle plate 9 with which the service pipe 12 is connected, an oil level gage 13, and an oil outlet opening 14 which is connected through a pipe 15 with an air intake pipe 16 connected with the intake port 4 of the 55 compressor. Pipe 15 is provided with a reg-

ulating valve 17 for purposes hereinafter to be described.

Chamber 8 is first of all provided as a reservoir for the sealing liquid which is circulated through the compressor, and secondly as a trap for separating the sealing liquid from the air discharging from the compressor.

In operation, chamber 8 is partly filled with oil or any other suitable form of liquid which is suitable both for sealing and lubricating purposes, the oil level being indicated or controlled by the position of gage 13. The compressor is then started and valve 17 opened. A flow of oil is thus permitted through pipes 15 and 16 and this oil will enter the cylinder with the incoming air; the quantity of oil thus admitted being regulated by valve 17 and should be sufficient to form a seal between the piston 75 vanes, with connected rotating parts, and the cylinder, also acting as a lubricant at the same time.

The oil after circulating through the compressor is permitted to discharge with the 80 outgoing air through pipe 10 and is separated from the air in the following manner: The oil discharging through pipe 10 is in a finely divided state or, practically speaking, in an atomized condition, and one 85 of the functions of chamber 8 is to separate the oil from the air to prevent it from passing out with the air into the service pipes where it would be lost and might be detrimental. The oil in the form of a spray discharging with the air against the upper surface in chamber 8 will, practically speaking, condense or collect on same and trickle down the sides and collect in the lower end of the chamber. The air will then pass in a downward direction under baffle 9, as indicated by arrow a, and will then finally escape through service pipe 12. The oil is thus 90 thoroughly separated from the air and will constantly collect in the lower part of chamber 8 where it is again permitted to escape through pipes 15 and 16 to be again circulated through the compressor. The operation 95 or circulation of oil through the compressor for the purposes specified is thus continuous and the loss or escape of oil through pipe 12 is so small that it is only necessary to replenish the supply in chamber 18 at great intervals. The oil thus circulated 100 does not only form a perfect seal 110

between the cylinder wall and the several rotating parts, but also forms an automatic lubricating system which is not only simple and automatic in action but also greatly increases the efficiency and life of the compressor.

The materials and finish of the several parts of the device are such as the experience and judgment of the manufacturer may 10 dictate.

I wish it understood that various changes in form, proportions, and minor details of construction may be resorted to within the scope of the appended claims and that I do 15 not wish to limit myself to the specific design and construction here shown.

Having thus described my invention, what I claim and desire to secure by Letters Patent is—

- 20 1. A separator for air compressors including a chamber having an outlet in its top and having its said top arched at one side of the outlet, a baffle plate connected to the top at the center thereof and extending downwardly therefrom and terminating in spaced relation to the bottom of the chamber, said baffle plate being disposed between the outlet and arched top to separate same, and a discharge pipe on one side of the baffle plate and abutting the latter and terminating adjacent the arched top so as to project the pipe discharge against the arched top and in a direction opposite to the outlet so as to cause the discharge to course downwardly 25 on one side of the baffle and then pass under the baffle and up the opposite side of the latter prior to reaching the outlet.
- 30
- 35

2. In a separator, a chamber having a closed top and an outlet on one side thereof, a vertical baffle plate connected to and depending from the top and disposed between said outlet and the other side of the chamber, said baffle extending down toward the chamber bottom and being spaced from the latter, and an inlet pipe at approximately 40 the center of the chamber extending on the side of the baffle opposite to the side on which the outlet is located and having a discharge located adjacent the top of the chamber to allow the discharge to engage the side 45 of the chamber adjacent said pipe prior to passing beneath the baffle.

3. In a separator, a chamber having an outlet on one side thereof, a baffle extending down from the top and disposed between 50 said outlet and the other side of the chamber, the lower end of the baffle terminating in spaced relation to the bottom of the chamber, and an inlet pipe extending up through approximately the center of the 55 chamber bottom and terminating adjacent the top of the chamber and being disposed on the side of the baffle opposite to the side on which the outlet is located, said pipe extending across the space between the lower 60 end of the baffle and the chamber bottom.

In testimony whereof I have hereunto set my hand in the presence of two subscribing witnesses.

DEXTER C. BAKER.
